CARD DISPLAY STAND

Theodore A. Hartman, Monroe, Wis.

Application May 2, 1951, Serial No. 15,041

Term of patent 14 years

(Cl. D80—9)

To all whom it may concern:

Be it known that I, Theodore A. Hartman, a citizen of the United States, residing at Monroe, in the county of Green and State of Wisconsin, have invented a new, original, and ornamental Design for a Card Display Stand, of which the following is a specification, reference being had to the accompanying drawings, forming part thereof.

Fig. 1 is a front elevational view of a card display stand, showing my new design;

Fig. 2 is a rear elevational view;

Fig. 3 is a side elevational view looking from the left in Fig. 1; and

Fig. 4 is a top plan view.

I claim:

The ornamental design for a card display stand, substantially as shown.

THEODORE A. HARTMAN.
